R. S. RHODES

SAFETY SWITCH

Filed Jan. 25, 1921

Fig. 1.

Fig. 2.

Inventor

ROBERT S. RHODES

By his Attorney

E. H. Bunting

UNITED STATES PATENT OFFICE.

ROBERT S. RHODES, OF BROOKLYN, NEW YORK, ASSIGNOR TO CONSOLIDATED CAR-HEATING COMPANY, OF ALBANY, NEW YORK, A CORPORATION OF WEST VIRGINIA.

SAFETY SWITCH.

Application filed January 25, 1921. Serial No. 439,812.

To all whom it may concern:

Be it known that I, ROBERT S. RHODES, a citizen of the United States, residing at New York city, borough of Brooklyn, in the county of Kings and State of New York, have invented certain new and useful Improvements in Safety Switches, the following being a full, clear, and exact disclosure of the one form of my invention which I 10 at present deem preferable.

For a detailed description of the present form of my invention, references may be had to the following specification and to the accompanying drawing forming a part 15 thereof, wherein

Figure 1 is a front view, and

Figure 2 a side view with the box or casing in section.

My invention constitutes an improvement 20 on a safety-switch devised by Lee P. Hynes and Percy M. Griffin, and shown in application Ser. No. 367,256 filed March 19, 1920.

Switches of this type are designed for use 25 with high voltages and the purpose is to provide for the operation of the switch from outside of the enclosing box or casing, so as not to expose the operator to the danger of contact with the live part of the switch mechanism. It is also desirable that the 30 operating handle shall be on the front of the box or casing instead of the side and that it have a considerable range of movement to provide the force necessary to compress the actuating spring of the switch.

35 In the switch of this kind shown in the aforesaid application Ser. No. 367,256, the handle moves in a slot formed in the front plate of the box and carries with it a sliding cover plate that lies across the slot to prevent contact with the interior members of 40 the switch, and also to prevent the emergence through the slot of any arc which may result from the rupture of the high-voltage circuit when the switch is opened. The handle is also arranged to prevent opening of 45 the box except when the switch is open.

50 My improvement resides in a form of switch handle which will itself maintain the closure of the slot in the casing through which it protrudes while at the same time permitting the desired range of movement of the handle. It likewise preserves the locking effect by which the handle prevents the opening of the box cover except when 55 it is moved to the switch-opening position.

Referring to the drawing A represents one side of the box or casing. A¹ represents a fixed section of the front face and A² A³ are hinged covers for the top and bottom portions of said front face of the box. A² 60 is hinged at a² and A³ at a³. The movable switch contact is shown at B, the stationary one at B¹. The coil of the blow-out magnet is shown at C. The pole-piece D extends below coil C and is secured to the 65 base F. By this arrangement the depth of the box is materially reduced. Inside of pole-piece D is the arc-chute E of insulating material surrounding the contacts B and B¹. The mechanism of the switch is not shown, 70 since snap-break switch mechanisms are well known in the art and I may use any desired form thereof; H is the operating lever of such a switch, and I secure thereto, as a handle, a disc-sector G of insulating material 75 which projects through a slot in the box as shown in the drawing. Outside of the box and projecting from the sides of disc-sector G are knobs G¹ which not only serve for operating the disc-sector but also prevent 80 the lifting of hinged cover A³ when the handle is in its full-line position, the switch being then closed. When, however, the handle is moved to its dotted-line position to open the switch, then the knobs G¹ are back 85 of the hinge a³ and the cover A³ can be turned up into its dotted-line position to give access to the lower part of the box for replacing a fuse or other purpose. Since the switch is necessarily open at this time, it is 90 safe to touch it, the only live point being the contact B¹ that is out of reach. In all its positions the disc-sector G completely fills the slot and thus avoids the need for the sliding cover heretofore used to cover the 95 slot as the handle moves to and fro therein.

What I claim as new and desire to secure by Letters Patent is:

1. A safety switch comprising a casing provided with a hinged cover having a slot 100 therein open at one end contiguous to the hinged portion of the cover, a switch handle extending through and normally filling said slot, and means on said handle co-operating with a portion of the cover contiguous to the closed end of the slot to prevent movement of the latter until the handle is moved to a predetermined position.

2. A safety switch comprising a casing provided with a cover hinged at one end, 110

said cover having a slot open at the hinged end, a switch handle operable in the slot, and means on said handle to prevent opening of the cover until the handle has been moved 5 to the open end of the slot.

3. A safety switch comprising a casing, a cover hinged at one end to said casing and provided with a slot open at the hinged end, a disk-like switch-actuating member pivotally supported and extending through said 10 slot, and means on said disk positioned to form a handle and co-operating with said slot to prevent opening of the cover until the disk is moved to a predetermined position.

4. A safety switch comprising a casing, a cover hinged at one end to said casing and having a slot extending to the hinged end, a pivotally supported disk-like sector extending through and normally filling said 15

slot, locking means on said disk forming a handle and co-operating with said slot to prevent movement of the cover until the locking means is moved to a position of clearance located beyond the hinged connection. 25

5. A safety switch comprising a casing, a stationary cover section having a slot open at one end, a cover hinged at one end and having a slot aligned and in register with 30 the slot of the stationary cover, a disk sector extending through and simultaneously filling both slots, and locking means on said disk sector normally preventing movement of the hinged cover until said locking means 35 is moved to a position over the slot in the stationary cover.

Signed at county and State of New York,
this 24th day of January, 1921.

ROBERT S. RHODES.
